PROCESS OF CRACKING NAPHTHA AND
HEAVIER OILS IN THE VAPOR PHASEAlbert P. Sachs, Brooklyn, N. Y., assignor to
Petroleum Conversion Corporation, New York,
N. Y., a corporation of Delaware

Application October 27, 1933, Serial No. 695,408

6 Claims. (Cl. 196—66)

The present invention relates to improvements in cracking hydrocarbon oils in the vapor phase to produce motor fuels of the gasoline type and more particularly to improvements in the type of process described in the patent to Beardsley and Colony #1,842,318, dated January 19, 1932. In this type of process the oil to be cracked is vaporized and the vapor, preferably superheated, is mingled with a heated gaseous heat carrier in a reaction chamber, the temperature of the heat carrier gas being sufficient to bring about cracking of the oil vapor with which it is mingled. In a further development of the process as exemplified in the patent to Beardsley #1,883,744 the products from the reaction chamber are scrubbed with an oil containing comparatively heavy fractions, which oil may be in whole or in part the stock charged to the system, the purpose of this step being on the one hand to remove from the cracked products a portion of their heat and also small quantities of free carbon which may be entrained as well as tar and very heavy ends, and on the other hand, to effect a fractionation of the stock introduced to the system at this point. Thus, conditions are maintained so that the overhead distillate from the scrubber contains not only the vapors of the motor fuel formed in the cracking zone but also the vapors of the oil to be cracked. The latter are dropped out in a suitable condensing unit or rectifier and are then fed to a vaporizer which furnishes the reaction chamber with vapors to be cracked.

The present improvement is founded upon my discovery that the output of a plant of the foregoing type designed to crack heavy oil, e. g., gas oil or heavier, can be materially increased if along with the heavier oil there is added to the system a quantity of naphtha to be cracked, whereby the output capacity of the system in gasoline can be materially increased. Naphtha while having an end boiling point not greatly different from that of gasoline is not suited for blending with gasoline because of its unsatisfactory boiling range and generally its objectionably low anti-knock rating. It is therefore desirable to reform the naphtha by cracking it into gasoline. Because of the nature of the cracking process on which my invention is an improvement and of the comparatively high volatility of the naphtha as compared with gas oil, for example, it is possible to operate the system with the usual amount of the heavy oil cracking stock plus a large quantity of naphtha without having to increase the capacity of any part of the cracking system other than possibly the gasoline condenser. The reasons

for this are as follows: In cracking oil in the vapor phase, a large proportion of the total heat required goes to furnish the latent heat of vaporization of the oil. Because of this fact that so much heat must be supplied at one point in the system, it is extremely difficult to increase the capacity of the system as a whole without installing additional vaporizing capacity. However, when the heavier oil, as for example gas oil, is diluted with a more volatile oil such as naphtha, the vaporization of the mixture is greatly facilitated, first, because the average boiling point of the mixture is much lower than the average boiling point of the gas oil, and second, because the naphtha when vaporized acts to reduce the partial pressure of the gas oil, or, in other words, functions in the manner of steam to facilitate vaporization. Thus, for example, if the capacity of a given vaporizer is one hundred gallons of fresh gas oil charge per unit of time, such a vaporizer can be caused to furnish vapor corresponding to one hundred gallons of fresh gas oil charge plus that corresponding to fifty gallons of naphtha per unit of time without increasing the fuel consumption substantially. Now, of course, the temperature of the mixture of the vapors leaving the vaporizer is correspondingly less than the temperature of the gas oil vapor alone would be but this deficiency in heat units can be made up in the superheating step which follows since a gas superheater has much greater flexibility and is much more capable of being overloaded than is a vaporizer. Furthermore, sufficient heat, or as it is generally termed, superheat, may be imparted to the vapor mixture in this manner so as to render it unnecessary to increase the ratio of carrier gas to oil vapor. Also by raising the cracking temperature slightly, say by 5 to 10° F. as by increasing the superheater temperature and/or the heat-carrier gas temperature, the rate of flow of the gas mixture through the reaction chamber can be increased so as to correspond with the increased velocity of the cracking due to the 5 or 10° F. higher temperature, the reaction velocity doubling for each 22° F. increase in temperature. This slightly higher temperature is, moreover, of advantage in that at a temperature still satisfactory for the cracking of gas oil it insures a high conversion of the naphtha, e. g., 1% or above (while insuring a 30% conversion of gas oil for example), which is desirable since, as above mentioned, the unconverted naphtha has a low anti-knock rating and its presence in gasoline is therefore to be kept at a minimum.

A further advantage of cracking the gas oil and naphtha together is that less heat is lost by radiation than would be the case if the two were cracked separately.

5 My invention will be best understood by reference to the following detailed description taken with the annexed drawing illustrative of a plant embodying my invention.

Referring to this drawing, the course of the 10 heavier oil will be first described. Here this charging stock, which may be gas oil or an oil containing both heavier and lighter ends than gas oil, is fed from a source of supply 10 through pipe 11 into a scrubber 12 wherein it comes into 15 contact with the hot products from the reaction chamber 14 fed therefrom through pipe 15. In the scrubber a portion of the heat in the reaction products is abstracted and the tar and carbon and such very heavy ends as are present 20 are dropped out and the hot oil residue is removed from the scrubber through a pipe 17. The heat in this oil is recovered in large part as is more fully described in Patent #1,833,744. After the oil has thus yielded up its heat, all 25 or a portion of it may be returned to the scrubber through a pipe 19. In the scrubber the charging stock is largely vaporized, conditions being maintained so that all the constituents which it is desired to crack subsequently are vaporized. The overhead distillate so produced is then led from the scrubber through pipe 21 into a rectifier 22 wherein the ends heavier than the motor fuel are dropped out. In order to maintain the proper temperature within the 30 rectifier 22 a portion of the residue is removed through pipe 23, is cooled in a cooler 24, and pumped back again into the top of the rectifier through a pipe 25. The vapors escaping condensation leave the rectifier through pipe 27 by means of which they pass to a condenser 28, the condensate being passed to an accumulator 29 through a pipe 30 while the uncondensed vapors pass from the condenser through a pipe 31 into the top of accumulator 29 and thence through a pipe 32 to an absorber 34 wherein the residual light ends are separated out, after which the stripped gas passes to a gas holder 36 storing the gas produced in the system. The gas holder 36 constitutes a source of supply of gas not only 35 for the cracking reaction but for various fuel purposes needed in the system. The liquid condensate from the rectifier 22, which contains the heavier ends to be cracked, is then withdrawn through pipe 38 leading to a vaporizer 40. The 40 naphtha to be cracked which may be stored in tank 41 is also admitted (after being suitably preheated, if desired, conveniently from a source of waste heat within the system, not shown) to the vaporizer 40, through pipe 41a leading into pipe 38. It will be noted that the material leaving the rectifier 22 through pipe 38 will contain both the fresh gas oil which has been redistilled and the gas oil that has been recycled for further cracking. The vapor formed is separated 45 from the unvaporized liquid in the flash drum 42 whereupon the vapor leaving such drum is superheated in the superheater 44, after which it passes through pipe 45 to the top of the reaction chamber 14. At the same time a necessary 50 quantity of heat-carrier gas is being heated up by one of the hot blast stoves 50 (or other heating device), such gas being admitted to the proper stove from pipe 47 and the hot gas is withdrawn through pipe 51, by means of which 55 it is discharged into the reaction chamber. It

will be understood that the battery of hot blast stoves 50 is arranged so that there is at all times a continuous supply of hot gas to the reaction chamber.

When the amount of gas oil being cracked is equal to the capacity of the vaporizer for gas oil alone, I may add to this a quantity of naphtha up to 50% by weight of the fresh gas oil charge without increasing the burden on the vaporizer. It will be noted that since a conversion of the 10 naphtha of 90% or over is obtained, as compared with a 30% conversion of the gas oil alone on one pass, in such a case there will be the usual amount of recycling with respect to the gas oil but substantially no recycling with respect to the 15 naphtha fraction. Thus the vaporizer will have to handle not an additional 50% by weight, but, if the recycle ratio of the gas oil alone is one part of recycle gas oil to one part of fresh feed only 25% more by weight. But the total 20 by weight of the "normal" charge will all vaporize at a considerably lower temperature than for gas oil alone so that the added heat burden or vaporizer load will be far less than 25% and for practical purposes may be disregarded. The 25 temperature of cracking will ordinarily vary from 950 to 1050° F. although these limits are not critical, and where the system has been adjusted to operate on gas oil alone at a given range of cracking temperature, the cracking temperature 30 to be chosen for the mixture of gas oil and naphtha may ordinarily be from 5 to 10° or more higher as above stated. The temperature of the vaporized gas oil alone would be ordinarily about 800° F. while the temperature of the vaporized 35 mixture of four parts gas oil and one part naphtha for example will ordinarily be less than 700° F. This vapor mixture is preferably superheated to a temperature of 930° F. to 980° F. or higher, although lower temperatures as for example 850° may be employed. This mixture 40 may then be brought into contact with heat-carrier gas of the type produced in the system, which may have a temperature of 1150° F. in the quantity of one pound of vapor mixture to 45 one-half pound of heat-carrier gas.

It will be understood that by gas oil is meant any oil having an initial boiling range of from 450° to 500° F. or higher. Furthermore, since gas oil itself is an overhead distillate, all or a 50 portion of the fresh feed may be admitted directly to the vaporizer 40, preferably after being preheated in some convenient manner. In case a large proportion of the gas oil is added to the vaporizer directly, the oil used for scrubbing 55 will after the system has reached a steady state consist of the heavier fractions which are produced from any cracking stock simultaneously with the desired gasoline fractions.

The above stated conditions have been given 60 by way of example and may be varied somewhat without departing from the spirit of my invention.

I claim:

1. The method of simultaneously cracking 65 naphtha and gas oil or oil of higher gravity in the vapor phase by the aid of a heated heat-carrier gas to produce motor fuels which consists in feeding a mixture of said oil and naphtha to a vaporizer wherein the naphtha is present in 70 sufficient quantity to lower substantially the partial pressure of said gas oil, superheating the vapor produced, then effecting cracking of the vapor by mingling it in a reaction chamber with the necessary quantity of the heated heat-car- 75

- rier gas, then after the reaction has taken place passing the mixture from the chamber and separating from said mixture the components suitable as motor fuels.
5. 2. The method of simultaneously cracking naphtha and gas oil or oil of higher gravity in the vapor phase by the aid of a heated heat-carrier gas to produce motor fuels which consists in feeding a mixture of said oil and naphtha to a vaporizer wherein the naphtha is present in sufficient quantity to lower substantially the partial pressure of said gas oil, superheating the vapor produced, then effecting cracking of the vapor by mingling it in a reaction chamber with the necessary quantity of the heated heat-carrier gas, then after the reaction has taken place passing the mixture from the chamber, dephlegmating said mixture by mingling therewith at least a portion of the gas oil fed to the system under conditions as to vaporize the constituents of the gas oil which it is desired to pass to the vaporizing zone, rectifying the overhead vapor mixture and passing the condensed gas oil fractions to the vaporizer.
10. 3. The method according to claim 2 in which no naphtha is fed to the dephlegmating or scrubbing chamber and in which the cracking reaction is continued until substantially all of the naphtha is converted so as to render the final product free 20 of uncracked or unconverted naphtha.
15. 4. The process according to claim 2 in which the temperature of the reaction is carried out at a slightly higher temperature than the temperature at which the gas oil would have been cracked 25 had the naphtha not been present.
20. 5. The method of simultaneously cracking 30 naphtha and gas oil or oil of higher gravity in the vapor phase by the aid of a heated heat-carrier gas which consists in feeding the mixture of said oil and naphtha to a vaporizer, the gas oil being in an amount substantially that of the capacity of the vaporizer when the gas oil alone is vaporized and the naphtha being in an amount from 5 to 25% by weight of the gas oil fed to said vaporizer, vaporizing said mixture, superheating the produced vapors of the naphtha and gas oil, 10 then effecting cracking of the mixed vapor by mingling it in a reaction chamber with the necessary quantity of heated heat-carrier gas, then after the reaction has taken place passing the mixture from the chamber and separating therefrom the components suitable as motor fuels.
25. 6. The method of simultaneously cracking naphtha and gas oil or oil of high gravity in the vapor phase by the aid of a heated heat-carrier gas which consists in feeding the mixture to a vaporizer, the gas oil being in an amount substantially that of the capacity of the vaporizer when the gas oil alone is vaporized and the naphtha being in an amount from 5 to around 25% by weight of the gas oil fed to said vaporizer, 25 vaporizing said mixture, superheating the produced vapors of the naphtha and gas oil at a temperature from 850 to 965° F., effecting cracking of the mixed vapor by mingling it in a reaction chamber with the necessary quantity of 30 heated heat-carrier gas so as to produce a cracking temperature of from 950 to 1050° F., then after the reaction has taken place passing the mixture to the chamber and separating the components suitable as motor fuels.

ALBERT P. SACHS.
